Primary Examiner — David Muller*Assistant Examiner* — Nathan Johnston(74) *Attorney, Agent, or Firm* — Peter Jo Flora(57) **CLAIM**

The ornamental design for an introducer hub, as shown and described.

DESCRIPTION

FIG. 1 is a front perspective view of an introducer hub according to my design;

FIG. 2 is a front perspective view thereof;

FIG. 3 is a bottom plan view thereof;

FIG. 4 is a top plan view thereof;

FIG. 5 is a front elevation view thereof;

FIG. 6 is a back elevation view thereof; and,

FIG. 7 is a side elevation view thereof.

The features shown in broken lines depict environmental subject matter only and form no part of the claimed design.
